Specification for Design.

Patented Feb. 1, 1921.

Application filed October 2, 1919. Serial No. 328,071. Term of patent 14 years.

To all whom it may concern:

Be it known that I, EARNEST E. MULLVAIN, a citizen of the United States, and resident of the city of Berkeley, county of Alameda, State of California, have invented a new, original, and ornamental Design for an Automobile-Signal, Case B, of which the following is a specification, reference being had to the accompanying drawing, forming a part thereof.

In the drawing:

Figure 1 is a front elevation of the signal, Fig. 2 is an end elevation, and

Fig. 3 a perspective view of the signal.

What I claim is:

The ornamental design for an automobile signal substantially as shown.

In testimony whereof, I have hereunto set my hand this 27th day of September, 1919, in the presence of the two subscribed witnesses.

E. E. MULLVAIN.
